PRINTED PICTURE MAT SHEET

Nathan George Horwitt, Lenox, Mass.

Application July 2, 1948, Serial No. 36,745

5 Claims. (Cl. 40—158)

1

The present invention relates to mats for use in framing or mounting pictures.

One object of the invention is the provision of a prefabricated mat sheet which may be readily formed into a mat having an opening for a picture of any one of a series of sizes within a relatively wide range of the most frequently used picture sizes.

Another object is the provision of a mat sheet which may be readily formed into a mat either for vertical pictures or for horizontal pictures, i.e., for pictures which should be framed or mounted with their longer dimension extending either vertically or horizontally depending upon the format or composition of the picture.

A further object is the provision of a mat sheet which may be readily formed into a plurality of picture mats in unitary relation for back-to-back framing or mounting of two pictures which may be either of the same size or of different sizes.

A further object is to provide a mat sheet for making mats which are sufficiently strong and sturdy and yet comparatively thin and light so that a large number of mounted pictures can be easily carried from place to place in a portfolio or package which is not bulky.

The above and other objects, features and advantages will be fully understood from the following description considered in connection with the accompanying drawings which are to be considered as illustrative of the invention but not in limitation thereof.

In the drawings:

Fig. 1 is a plan view of a mat sheet embodying the present invention;

Fig. 2 is a front perspective view of a picture mounting illustrating one manner of utilizing the mat sheet of the present invention; and

Fig. 3 is a sectional view on a larger scale on the line 3—3 of Fig. 2.

Referring now to the drawings in detail, the mat sheet 10 embodying the present invention is preferably formed of paper but may be made of other suitable sheet material. The mat sheet is preferably thinner than the usual picture mat which is formed of paper; for example, but without limitation, mat sheet 10 is desirably made of opaque non-coated paper stock of 120 lb. basis book paper weight.

Sheet 10 comprises sections 12 and 14 disposed at opposite sides of a central fold line 16. Said sections are preferably of the same size and shape so that when they are folded one over the other at fold line 16 their corresponding side edges are in registry with each other. As here shown,

2

section 12 is intended to be used for forming a mat for a vertical picture, and section 14 is intended to be used for forming a mat for a horizontal picture. The surfaces of these sections are preferably provided with vertical and horizontal co-ordinate lines printed thereon, the adjacent parallel lines of each section being preferably, but not necessarily, one-fourth of one inch apart. The vertical lines of section 12 are indicated at 18 and the horizontal lines of said section are indicated at 19; the vertical lines of section 14 are indicated at 22 and the horizontal lines at 24.

Vertical-picture mounting section 12 is provided with a series of rectangular outlines 26, 28, 15 30, 32 and 34 of different sizes, respectively.

These outlines are printed or otherwise delineated on the mat sheet and they correspond in dimensions to those of the most frequently mounted pictures, particularly photographic prints. Such

dimensions are usually 4 x 5, 5 x 7, 8 x 10, 9 x 12, and 11 x 14, inches, for outlines 26, 28, 30, 32, and 34, respectively, but of course may be different.

The margin of section 12 which is outwardly beyond outline 34 and which is provided with the co-ordinate lines 18 and 19 enables said section to be used for larger pictures. The outlines 26 to 34 are symmetrically arranged with respect to a common center point 36. The latter is the point of intersection of the orthogonal

vertical line 38 and the horizontal line 40 which are at right angles to each other. Said lines are scaled in inches, forming vertical and horizontal scales the zero point of each scale being at center point 36, with the scale on each line increasing

in each of the two directions along said line from said zero and center point 36. Each of the outlines is provided with a cutting line indication 42 which is preferably a dotted line printed or otherwise suitably delineated on the mat sheet.

Said cutting line indications 42 are disposed within their companion picture-size outlines 26 to 34, respectively, in appropriately spaced lateral relation thereto, the spacing being preferably about one-fourth of one inch. The picture-size outlines

45 and the cutting-line indications may be printed in contrasting colors, say black and red, respectively, and the scale lines 38 and 40 may be printed in a different color, say gray. The coordinate or orthogonal lines 18 and 19 are preferably thin

50 and may be black or any other color. The scale lines 38 and 40 are conveniently the thickest of all the lines, and the picture-size outlines are next in thickness.

It will be noted that the co-ordinate-lined part 55 of section 12 is spaced vertically from the lower

edge 44 of the latter as indicated by the blank space 46. Thus center point 36 is closer to the top edge 48 of section 12 than it is to the lower edge 44. Accordingly, the opening, which is provided in the mat by cutting it at the cutting line indication 42 within the picture-size outline, is properly positioned with its upper edge closer to the upper edge of the mat or frame than is the lower edge of said opening in respect to the lower edge of the mat or frame, which position of the opening is in accordance with recognized principles of picture mounting or framing as will be readily understood.

Referring now to horizontal picture section 14, it will be evident from the drawings that this section is of the same character as section 12 except that it is displaced 90° in relation to section 12 on mat sheet 10. The parts of section 14 not yet specifically referred to are designated by the same reference numerals as the corresponding parts, respectively, of section 12 but with the letter "a" added. Accordingly, further description of section 14 in detail is unnecessary.

In order to form a mat from mat sheet 10, it is merely necessary to cut the same to provide the picture opening. Thus, assuming that it is desired to prepare the mat for a 4" x 5" "vertical" picture, the mat sheet is cut along the line 42 within the outline 26 of section 12, forming an opening of the appropriate size for such picture. Then, the picture is adhesively secured in position, the adhesive being applied between the picture-size outline 26 and the edge of the opening. The borders or margins between the picture-size outlines and their companion cutting line indications 42 may be coated with a suitable adhesive, a removable paper covering being provided, if necessary, so that the mat sheets 10 may be made and sold with the adhesive already applied, for the convenience of the user. This adhesive may be applied, desirably, in the form of bands of about one-fourth inch wide along or parallel to the scale lines 38, 40 and 38a, 40a. It will be understood that the lined surface of the mat sheet is at the back of the mat and that the front surface of the mat sheet, and of the method formed therefrom, is plain or may be provided with a suitable surface design or ornamentation, if so desired. It will be noted that the centering of the picture in relation to the opening of the mat is facilitated by the scale lines 38 and 40 and by the vertical and horizontal co-ordinate lines. The mat for a "horizontal" picture is prepared in the same way from section 14. Also, it will be understood that two mats in unitary relation for mounting two pictures in back-to-back relation may be prepared from the same mat sheet 10. If only one picture is to be mounted, the un-used mat section may be cut off at the fold line 16, for separate use in making another mat, but ordinarily it is much more preferable and advantageous to leave the un-used section attached to the mat and to fold the same over the back of the picture as a back cover therefor.

The picture or pictures thus mounted on the mat or mats formed from sections 12 and 14, as the case may be, may be left without framing, as for example, when the mounted pictures are to be kept in a portfolio or carried from place to place for exhibition or sale, or such mounted picture may be covered with a glass plate or the like, as indicated at 50 in Fig. 2. When the pictures are mounted back-to-back as shown in Fig. 3, a glass plate 50 may be provided over each of the

two mats. These glass covered pictures, mounted on their mats, may be suspended by adjustable brackets 52 such as those shown for example in my U. S. Patent No. 2,209,972.

While I have shown and described the presently preferred embodiment of my invention, it will be understood that changes may be made without departing from the underlying idea or principles of the invention within the scope of the appended claims.

Having thus described my invention, what I claim and desire to secure by Letters Patent, is:

1. A pre-fabricated mat sheet for making a picture mat, said sheet being formed of sheet material and having on its back surface a plurality of picture-size outlines of different sizes for pictures of different sizes, respectively, said outlines being symmetrically arranged on said surface with respect to a common center point, and a plurality of mat-opening cutting line indications on said surface of the sheet, one for each of said picture-size outlines, located inwardly of said picture-size outlines, respectively.

2. A pre-fabricated mat sheet for making a picture mat, said sheet being formed of sheet material foldable about a central line and having thereon two sets of picture-size outlines, each of said sets of outlines comprising a plurality of picture-size outlines of different sizes for pictures of different sizes, respectively, one of said sets of outlines being disposed on the sheet at one side of said fold line and the other of said sets of outlines being disposed at the other side of said fold line, the outlines of each set being symmetrically arranged on said sheet with respect to a common center point, and a plurality of mat-opening cutting line indications on said sheet, one for each of said picture-size outlines, located inwardly of said picture-size outlines, respectively.

3. A pre-fabricated mat sheet for making a picture mat, said sheet being formed of sheet material foldable about a central line and having thereon two sets of picture-size outlines, each of said sets of outlines comprising a plurality of picture-size outlines of different sizes for pictures of different sizes, respectively, one of said sets of outlines being disposed on the sheet at one side of said fold line and the other of said sets of outlines being disposed at the other side of said fold line, the outlines of each set being symmetrically arranged on said sheet with respect to a common center point, and a plurality of mat-opening cutting line indications on said sheet, one for each of said picture-size outlines, located inwardly of said picture-size outlines, respectively, all of said outlines being on the same surface of said sheet.

4. A pre-fabricated mat sheet for making a picture mat for either vertical or horizontal mounting of a picture, said sheet being of greater length than width and foldable about a central line extending along the width of the sheet, said sheet having thereon two sets of picture-size outlines disposed on said sheet at opposite sides, respectively, of said fold line, each of said sets of outlines comprising a plurality of picture-size outlines of different sizes for pictures of different sizes, respectively, the outlines of each set being symmetrically arranged on said sheet with respect to a common center point, each of said outlines being rectangular with the adjacent sides of each rectangle of unequal length and the longer sides of the rectangles extending widthwise of the sheet, said center point of one of

said sets of outlines being located midway between said fold line and the nearest opposite widthwise edge of the sheet, and said center point of the other of said set of outlines being located midway between two opposite lengthwise edges of the sheet, whereby the outlines of one of said sets are arranged for vertical mounting of the picture and the outlines of the other set are arranged for the horizontal mounting of the picture.

5. A pre-fabricated mat sheet for making a picture mat for either vertical or horizontal mounting of a picture, said sheet being of greater length than width and foldable about a central line extending along the width of the sheet, said sheet having thereon two sets of picture-size outlines disposed on said sheet at opposite sides, respectively, of said fold line, each of said sets of outlines comprising a plurality of picture-size outlines of different sizes for pictures of different sizes, respectively, the outlines of each set being symmetrically arranged on said sheet with respect to a common center point, each of said outlines being rectangular with the adjacent sides of each rectangle of unequal length and the longer sides of the rectangles extending widthwise of the sheet, said center point of one of said sets of outlines being located midway between said fold line and the nearest opposite widthwise

edge of the sheet, and said center point of the other of said set of outlines being located midway between two opposite lengthwise edges of the sheet, whereby the outlines of one of said sets are arranged for vertical mounting of the picture and the outlines of the other set are arranged for the horizontal mounting of the picture, and a plurality of mat-opening cutting line indications on said sheet, one for each of said picture-size outlines, located inwardly of said picture-size outlines, respectively.
